UNITED STATES PATENT OFFICE

1,937,789

COPYING MACHINE

Lewis J. Sauer, Oak Park, Ill., assignor to
Charles H. Joy, Sr., Chicago, Ill.

Application March 25, 1929. Serial No. 349,876

15 Claims. (Cl. 101—133)

This invention relates to copying machines, and more particularly to that class of machines commonly known as hectographs or duplicating machines and having a flat printing bed over which is stretched a long and comparatively thin gelatinized band or apron, the ends of the band being secured to and wound upon rolls or spools adjacent the ends of the printing bed, so that by rotating the spools successive sections of the band may be exposed in operative position on the bed.

In this type of machine a platen carriage having a suitable platen roller is adapted to travel over the printing bed for impressing the original or the copy sheets on the gelatinized band which receives the imprint from the original sheet and transfers it to the copy sheet.

One of the objects of my invention is to provide an improved means for moving the gelatinized band over the printing bed in either direction.

Another object is to provide a means whereby either of the band supporting spools may be individually and operatively connected to a single operating means for moving the band in the desired direction.

Another object is to provide an adjustable, automatic means for obtaining a desired margin on the copies.

It is also an object to provide an improved means for positively driving the platen roller as the carriage is moved over the bed of the machine.

Further objects will appear from the detailed description to follow and from the appended claims.

In the drawings, Figure 1 is a perspective view of a complete machine constructed in accordance with my invention;

Fig. 2 is a perspective view of the end of the carriage illustrating its adjustment with relation to the printing bed;

Fig. 3 is a longitudinal section taken on line 3—3 of Fig. 1;

Fig. 4 is a fragmentary longitudinal section similar to Fig. 3 with the band supporting spools removed and a portion broken away to show the spool operating mechanism;

Fig. 5 is a vertical transverse section taken on line 5—5 of Fig. 4;

Fig. 6 is a section taken on line 6—6 of Fig. 4;

Fig. 7 is a perspective view of the combined shaft supporting bracket and bearing;

Fig. 8 is a perspective view of the clutch shaft;

Fig. 9 is a section on line 9—9 of Fig. 5 and illustrates the spool bearing;

Fig. 10 is a perspective view of one of the spools;

Fig. 11 is a side view of the machine, parts being broken away to better illustrate the mechanism for controlling the operation of the platen roller and adjustable margin bar;

Fig. 12 is a perspective view of the gripping roll supports;

Fig. 13 is a front elevation of the carriage and cooperating parts of the machine, the carriage guide rod and a portion of the frame being shown in section;

Fig. 14 is a section taken on line 14—14 of Fig. 13;

Fig. 15 is a section on line 15—15 of Fig. 14, a portion being shown in full lines;

Fig. 16 is a section on line 16—16 of Fig. 14; Fig. 17 is a perspective view of the platen roll bearing;

Fig. 18 is a section taken on line 18—18 of Fig. 4;

Fig. 19 is a section on line 19—19 of Fig. 11 illustrating the frame adjusting and locking means;

Fig. 20 is a section on line 20—20 of Fig. 11 and illustrates the margin bar control dial;

Fig. 21 is a sectional view of a portion of the margin bar showing the notches to facilitate the paper removal;

Fig. 22 is a perspective view of the adjustable carriage stop;

Fig. 23 is a perspective view of the guide rod adjusting bushing;

Fig. 24 is a vertical section through the carriage guide rod support and carriage bumper;

Fig. 25 is a vertical section taken on line 25—25 of Fig. 11 through the carriage shock absorber;

Fig. 26 is a top view of the platen roller driving spool and cable and showing the position of the cable when the carriage is travelling in the direction of the arrow;

Fig. 27 is a section taken on line 27—27 of Fig. 26;

Fig. 28 is a top view showing the position of the cable on the spool when the carriage is travelling in the opposite direction from that shown in Fig. 26; and

Fig. 29 is a view of the driving spool with the cable removed.

Referring now to the drawings in detail, my invention as illustrated comprises a pair of side frames 1 and 2 on which is supported the printing bed plate 3, shown in Fig. 3, and which is covered with the felt or other suitable material 4. 110

The bed plate 3 is supported on the lugs 5 and prevented from end movement by means of the cross members 6 and 7 which are secured to the side frames and act as spacers therefor, the front ends of the side frames being connected by means of the tie rod 8.

Adjustable tie rods 9 are provided for accurately lining up the side frames as illustrated in detail in Fig. 19. The rods are threaded at each end, one end being screwed into the threaded lugs 10 on the side frame 2 and secured by means of the lock nut 11. A countersunk hole 12 extending through the frame 1 is adapted to receive the internally threaded flathead screw 12a which is screwed onto the rod 9. It will be noted that by turning the screw 12a on the rod 9 a very fine adjustment of the frame may be had and it may then be locked in position by tightening the nut 13 against the lug 14. This rigid support and easy adjustment of the frame of the machine is very important to the accurate operation and alignment of the carriage and other moving parts to be described later.

The depending feet 15 on the side frames support the integral frame structure described above.

The felt covering 4 affords a suitable surface for the gelatine band 16 which is of a length much greater than that of the printing bed and is wound upon the spools or spindles 17 and 18 which are rotatably supported below and adjacent the ends of the bed as shown in Fig. 3. By turning one of the spools successive sections of the gelatine band may be moved to exposed position and in either direction as desired.

The spools 17 and 18 are rotated in the desired direction by means of the hand wheel 19. When the hand wheel is turned in the direction of the arrow, Fig. 3, the spool 17 is rotated in the same direction while the spool 18 is disconnected from the driving mechanism and is free to rotate to allow the gelatine band to be unwound therefrom and to be wound upon the spool 17. When the hand wheel is turned in the opposite direction the operation is reversed and the spool 18 is rotated to wind the band thereon and the spool 17 is free to rotate and allow the band to unwind.

The means for controlling the operation of the spools is fully illustrated in Figs. 3 to 8, inclusive, and Fig. 18.

The contour of the cross section of the side frame 2 is such as to inclose the operating mechanism within the confines of the side frame. The hand wheel 19 is provided with a suitable handle 20 and secured on the longitudinally movable clutch shaft 21, Figs. 5 and 8, on which are integrally formed the clutch teeth 22 and 23. The clutch shaft is mounted in a suitable bearing bracket 24 which is secured in place by means of the screw 25.

A ratchet wheel 26 having an outwardly extending hub 27, and inwardly extending clutch teeth 28 is rotatably mounted in the cover plate 29 which encloses the chamber 30, the cover plate 29 being secured in place by means of the screws 31 on one of which is pivoted the pawl 32 for engagement with the ratchet 26. The clutch shaft 21 extends into the hole 33 in the ratchet wheel 26 and is longitudinally movable therein sufficiently to allow the clutch to be engaged and disengaged.

A spiral gear 34 is mounted on the shaft 21 and provided with clutch teeth 35 adapted to be engaged by the clutch teeth 23 on the shaft 21. A spacer ring 36 is loosely mounted around the

clutch in order to hold the spiral gear 34 and the ratchet wheel 26 in correct spaced relation.

When the hand wheel is turned in one direction, see Fig. 5, the clutch teeth 23 on the shaft 21 will engage the teeth 35 on the spiral gear 34 and rotate the gear in the same direction. When the wheel is turned in the opposite direction the shaft is automatically moved longitudinally, due to the incline of the clutch teeth, and the teeth 22 will engage the teeth 28 on the ratchet wheel 26 thus turning the spool 17 to wind the gelatinized band thereon.

The spools 17 and 18 are reversible and interchangeable and are provided with the bearing spindles 37 and the flattened portions 38, one of the spindles 37 being supported in the centering hole 39 in the ratchet wheel hub 27, the flattened portion 38 being engaged by the walls of the slot 40. The opposite ends of the spools are supported in suitable bearings in the side frame 1.

The bearing 41 of the bracket 24 extends through the side frame 2 and supports the bearing 42 formed integral therewith, in which is supported the transmission shaft 43 on which is mounted the spiral gear 44 which is driven from the gear 34.

The transmission shaft 43 extends rearwardly within the confines of the frame 2 and is arranged to drive the spool 18 through the spiral gear 45 (Fig. 6) which is mounted thereon, and the gear 46 which is rigidly secured to the shaft 47 on which is mounted the spool 18. The shaft is provided with the centering hole 48 and the slot 49 to receive the ends of the spool.

The ratchet 50 is rigidly mounted on the shaft 47 and is adapted to be engaged by the pawl 51 which is pivoted on one of the screws 52 supporting the cover plate 53. The cover plate provides the front bearing for the shaft 47 which is supported in the bearing 54 forming a part of the bearing bracket 55. The bracket 55 is similar to the front bracket 24, having a bearing 56 formed integral therewith to support the transmission shaft 43, and is held in position by the screw 57.

It will be noted that when the pawls 32 and 51 are in engagement with the ratchet wheels 26 and 50, respectively, Fig. 4, the spools cannot be rotated to unwind the gelatine band from either of the spools, and any desired portion of the band will be held snugly in position on the printing bed, the pawls preventing any movement of the printing surface.

When it is desired to wind the band in either direction it is necessary to disengage the pawls. This is accomplished by pulling forward the hand lever 58, Figs. 4 and 18, on the shaft 59, supported in a suitable bearing in the side frame 2. An arm 59 on the shaft engages in the notch 60 in the cam bar 61 and the bar can be moved longitudinally by this arrangement. When the cam bar is moved forwardly the cam surfaces 62 and 63 engage the pins 64 and 65, respectively, on the pawls 32 and 51 thus disengaging the pawls from their respective ratchet wheels.

By the above arrangement, when the hand wheel is turned forwardly as shown by the arrow A in Fig. 3 and the pawls are disengaged, the clutch is engaged to turn the front spool 17 to wind the gelatine band thereon. When the hand wheel is turned in the reverse direction the mechanism for turning the spool 18 is engaged and the spool 17 is free to unwind. When the desired gelatine surface is exposed on the printing bed, the pawls are again engaged and the band may be stretched as snugly as desired by turning the

hand wheel slightly in either direction as desired.

Both of the spools are provided with similar bearings in the side frame 1, Fig. 9, comprising the bearing notch 66 to receive the spindle 37 which is held therein by the latch 67 which is pivoted on the frame and held in raised position by means of the spring 68. That portion of the latch adjacent the slot is provided with the cam surface 67a. When it is desired to insert the 10 spool the spindle 37 is inserted between the latch and the frame, as shown by the dotted lines, and pushed inwardly forcing the latch down and allowing the spindle to enter the notch.

The spool may be removed by pulling outwardly 15 against the cam surface 67a which also forces the latch down. The spools may be inserted or removed without manual operation of the latch.

The carriage 69 is arranged to be moved over the printing bed and comprises a substantially 20 rectangular frame having a bearing 70 slidably mounted on the guide rod 71 which is supported by the ears 72 on the frame 1. By this arrangement the carriage may be moved over the printing bed or raised to permit removal of the band.

25 The opposite end of the carriage is supported on the side frame 2 by means of the roller 73, Fig. 2, which is adjustably mounted on the frame and the height of which may be adjusted by means of the screw 74 and the lock screw 75.

30 The guide rod 71 is provided at each end with split eccentric bushings 76, Figs. 23 and 24, which may be locked by the screw 77. By turning these bushings and properly adjusting the roller 73, the platen roller carried by the carriage may be made to travel with an even pressure over the entire printing bed. A rubber bumper 78 is mounted on the guide rod and secured by the ring 79.

The platen roller 80, Fig. 14, is mounted in the yoke 81 which is in turn pivoted on the rod 82, the springs 83 tending to force the yoke to the raised position shown in Fig. 11. The yoke may be moved to operative position by means of the handle 84. In order to lock the yoke in operative position against the tension of the spring 83 an automatic lock is provided comprising the cam 85 on the rod 86 which is movably mounted in suitable bearings on the yoke 81 and which is provided with the handle 87. The cam is normally held in the position shown in Fig. 14, by the spring 88, Fig. 15, in which position the yoke is held in operative position by the pin 89 on the carriage against which the outer edge of the cam rests. When the handle 87 is operated the rod 86 is turned until the cam slips below the pin 89 and the yoke and platen roller return to the position shown in Fig. 11.

When it is desired to lower the platen roller it is only necessary to push on the handle 84 until the cam returns to the locked position.

35 When the carriage is moved to the extreme front position the arm 90 on the cam engages the pin 91 on the side frame and the yoke is automatically released. The yoke is limited in its downward movement by the adjustable stops 92 on the carriage, Fig. 3.

Each end of the platen roller is mounted in spring bearings comprising the bearing block 93 (Fig. 17) which is adapted to be inserted from the side into the opening 94 and is retained therein 40 by the shoulders 95 and the plug 96 in the hole 97 which is pressed downwardly by the spring 98. A spring pressure is thus obtained by the platen roller against the printing surface. The bearing block 93 may be removed by removing the platen 45 roller and pushing up the plug 96 by inserting

a wire through the hole 97. The roller is held in place when the yoke is raised by the spring controlled latch member 99, pivoted on the yoke, which extends under the shaft 100 of the roller and is limited in its movement by the lug 101 extending into the hole 102 in the yoke. The spring 103 controls the member 99 which may be released by the handle 104.

The usual gripping roll 105 (Fig. 12) is mounted in spring supports comprising the bearing members 106 having threaded extensions 107 slidably mounted in the carriage frame and adjusted to prevent forward movement, by the lock nuts 108. A spring 109 is supported in a hole in the bearing member and tends to exert a spring pressure between the carriage frame and the bearing block.

The platen roller in its downward movement presses the gripping roller rearwardly and carries the paper which is inserted between the 95 rolls, down against the gelatinized band. The paper is guided during insertion by the plate 110 having the fixed stop 111 and the movable stop 112.

The paper is inserted between the rolls until 100 it is stopped by the raised back of the adjustable margin bar 113, (Figs. 3 and 11) the position of this bar determining the margin.

The margin bar is provided with forwardly extending arms 114 and 115 which are pivoted to 105 the levers 116 and 117 respectively and are supported thereon by the pins 118. The margin bar may be turned forward to rest upon the tie rod 8 (see dotted lines in Fig. 3), when it is desired to remove or insert the gelatin band. The levers 110 116 and 117 are pivoted at 119 and 120 respectively and in alignment on the frames 1 and 2 so that when the levers are raised the margin bar will be moved from the position shown in full lines in Fig. 11, to the position shown in dotted 115 lines, and the position at which it is stopped in its upward movement will determine the width of the margin.

A lever 121 is pivoted at 122 on the side frame 1 and is connected to the lever 116 by the spring 120 123, the spring being normally not under tension and therefore the margin bar will remain in its lowest position when the carriage is travelling over the printing bed.

In order to automatically raise the margin 125 bar the upwardly extending arm 124 of the lever 121 is arranged to be engaged by the carriage frame when it is moved to its extreme forward position thus putting the spring 123 under tension and tending to raise the bar. In order that 130 the margin bar may remain in the position shown or be allowed to raise to any predetermined position the arm 125 on the lever 116 is arranged to engage one of the pins 126 which are arranged in cam-like formation on the disc 127. The disc 135 127 may be rotated to any desired position by the dial 128, the legends on the dial corresponding to the margins desired. It is evident that a cam may be used instead of the pins thus obtaining an infinite number of positions for the 140 margin bar if desired. A ball 129 engages in notches in the dial to hold it in the desired position, the ball being held against the dial by the spring 130.

The margin bar is provided with notches 131, 145 Fig. 21, to allow the paper to be easily removed from the gelatin when very little margin is allowed.

A adjustable stop is provided for the carriage comprising a spring steel strap 132 (Fig. 22) 150

around the guide rod 71 and having outwardly extending arms 133 and 134, the end of the arms 133 being turned downwardly to engage the arms 134 and keep the arms in spaced relation when the strap is clamped tightly on the rod by means of the clamping screw 135 which is threaded into the arm 134.

The carriage may be raised from the printing bed and turns on the guide rod 71 as shown by the dotted lines in Fig. 25. In order that it may not be damaged by dropping on the frame, the dash-pot shock absorber 135a is provided on the carriage, comprising a piston 136 on which is mounted the roller 137 for engagement with the frame 1. The piston is slidably mounted in the chamber 133 and pressed downwardly by the spring 139. A needle valve 140 allows adjustment of the air outlet 141. A pin 142 in the slot 143 limits the movement of the piston. When the carriage is raised the piston is pushed outwardly and if it is dropped the confined air provides a suitable cushion.

It is important that the rotation of the platen roller should be positive with relation to the printing bed, and this is accomplished by the means illustrated in Fig. 11 and Figs. 26 to 29, inclusive, in which a single turn of the cable 144 engages the flanged pulley 145 on the platen roller shaft 189. The cable rotates the pulley and platen roller when the carriage is moved. The cable is attached to the bracket 146 at the rear of the machine by means of the spring 147, and to the pulley 145 at the front. The pulley 145 being arranged to travel on the bracket 149 to allow the carriage to be raised and still keep the cable approximately in alignment.

In order that that portion of the cable in the direction from which the carriage is travelling should always be in alignment with the center of the pulley 145 a very shallow groove 150 is provided in the exact center of the pulley. It has been found that with this construction the cable will take the position shown in Figs. 26 and 27 when the carriage travels in the direction of the arrow A, and when the carriage travel is reversed to travel in the direction of the arrow B the cable will take the position shown in Fig. 28, and in each case the pull of the cable will be in the center of the pulley with no tendency to creep in either direction. This pulley construction makes it possible to use a very narrow pulley, even the flanges being unnecessary except for convenience in assembly.

Having thus described my invention, what I claim as new and desire to secure by Letters Patent is:

1. A duplicating machine comprising a bed over which the gelatine roll passes, a carriage movable back and forth above said bed, means for applying and removing a sheet of paper with respect to the gelatine roll comprising a roller mounted on said carriage and extending across and adjacent said bed, and means for causing rotation of said roller as said carriage is moved back and forth comprising a flexible member extending alongside said bed and a pulley about which said flexible member passes, said pulley having a central circumferential groove to receive a wrap of the flexible member and having a circumferential surface on each side of said groove wide enough to accommodate the flexible member and having circumferential flanges for confining the flexible member to said circumferential spaces, whereby when the carriage is moved in one direction the then taut portion of the

flexible member will lie in the groove and the slack portion will lie on one of said circumferential spaces and whereby when the carriage is moved in the opposite direction thereby reversing the taut and slack portions of the flexible member the then taut portion will lie in the groove and the then slack portion will lie on the other of said circumferential spaces. 80

2. A duplicating machine comprising a bed over which the gelatine roll passes, a carriage movable back and forth over said bed, a platen roller for applying the paper to the gelatine roll, a roller support shiftably mounted on said carriage for moving said platen roller into and out of paper applying position, a stop for limiting the shifting movement of said support, and means for yieldingly mounting said roller on said support to permit it to ride over inequalities in the paper. 85 90

3. A duplicating machine comprising a framework, a bed mounted on said frame over which the gelatine roll passes, a carriage shiftable back and forth above said bed, a platen roller mounted on said carriage, a margin bar movably mounted on said framework for adjustment with respect to said roller, means controlled by the movement of 100 the carriage for moving said margin bar, and adjustable means for limiting the movement of said margin bar. 95

4. A duplicating machine comprising a framework, a bed mounted on said frame over which 105 the gelatine roll passes, a carriage shiftable back and forth above said bed, a platen roller mounted on said carriage, and a margin bar movably mounted on said framework for adjustment with respect to said roller, means for limiting the 110 movement of said margin bar, and yielding means for holding said bar at the limit of its movement.

5. A duplicating machine comprising a framework, a bed mounted on said frame over which 115 the gelatine roll passes, a carriage shiftable back and forth above said bed, a platen roller mounted on said carriage, and a margin bar movably mounted on said framework for adjustment with respect to said roller, means for limiting the move- 120 ment of said margin bar, yielding means for holding said bar at the limit of its movement, and means whereby said yielding means are made effective by movement of said carriage.

6. A duplicating machine comprising a frame- 125 work, a bed mounted on said frame over which the gelatine roll passes, a carriage shiftable back and forth above said bed, a platen roller mounted on said carriage, and a margin bar pivotally mounted on said framework for two different 130 swinging movements about two different axes, one for adjustment of the bar with respect to the roller, and the other for movement of the bar from a position adjacent the bed to a position 135 to permit the gelatine roll to pass between said bed and margin bar.

7. A duplicating machine comprising a frame- 140 work, a bed mounted on said frame over which the gelatine roll passes, a carriage shiftable back and forth above said bed, a platen roller mounted on said carriage, and a margin bar movably mounted on said framework for adjustment with respect to said roller, the stop portion of said bar being movable from its paper edge engaging po- 145 sition to a position in which it is withdrawn from the paper edge and lies adjacent said bed, said bar having recesses therein between the stop portion and the adjacent portion of the bed to provide clearance for the fingers of the operator to 150

- reach the edge of the paper for removing it from the gelatine roll.
8. A duplicating machine comprising a bed over which the gelatine roll passes, a carriage movable back and forth over said bed, a roller frame pivotally mounted on said carriage to swing about a horizontal transverse axis, a platen roller mounted on said frame, means for latching said frame in lowered position, means for automatically unlatching said latch at a predetermined stage of the carriage movement and additional manually operable means for releasing said latching means at any stage of movement of the carriage, said roller frame being provided with a handle for operating it and said manually operable releasing means comprising a manually operable member adjacent said handle.
9. A duplicating machine comprising a bed over which the gelatine roll passes, a carriage movable back and forth over said bed, a roller frame pivotally mounted on said carriage to swing about a horizontal transverse axis, a platen roller mounted on said frame, means for latching said frame in lowered position, means for automatically unlatching said latch at a predetermined stage of the carriage movement and additional manually operable means for releasing said latching means at any stage of movement of the carriage, said roller frame being provided with a handle for operating it and said manually operable releasing means comprising a manually operable member adjacent said handle.
10. A duplicating machine comprising a bed over which the gelatine roll passes, a carriage movable back and forth over said bed, a roller frame pivotally mounted on said carriage to swing about a horizontal transverse axis, a platen roller mounted on said frame, means for latching said frame in lowered position, and manually operable means for releasing said latching means at any stage of movement of the carriage, said roller frame being provided with a handle for operating it and said manually operable releasing means comprising a manually operable member adjacent said handle.
11. A duplicating machine comprising a framework, a bed mounted on said frame over which the gelatine roll passes, a carriage shiftable back and forth above said bed, a platen roller mounted on said carriage, a margin bar swingably mounted on said framework for adjustment with respect to said roller, means controlled by the movement of the carriage for moving said margin bar, and adjustable means for limiting the movement of said margin bar.
12. A duplicating machine comprising a framework, a bed mounted on said frame over which the gelatine roll passes, a carriage shiftable back and forth above said bed, a platen roller mounted on said carriage, a shiftable margin bar support, and a margin bar shiftable mounted on said support to move from a position adjacent the bed to a position to permit the roll to pass between the bed and the margin bar, said margin bar support having provision whereby it is shifted by movement of the carriage.
13. A duplicating machine comprising a framework, a bed mounted on said frame over which the gelatine roll passes, a carriage shiftable back and forth above said bed, a platen roller mounted on said carriage, a pivotally mounted margin bar support, and a margin bar pivotally mounted on said support to move from a position adjacent the bed to a position to permit the roll to pass between the bed and the margin bar, said margin bar support having provision whereby it is shifted by movement of the carriage.
14. In a duplicating machine, in combination with a printing surface, a carriage, means mounting the carriage for reciprocation over the printing surface, an impression member journaled in said carriage, means locking the member in depressed position, a trip lever adapted to be manually actuated for releasing said locking means when desired, and other means automatically releasing said locking means when the carriage is located in its forward position.
15. A duplicating machine comprising a bed over which the gelatine roll passes, a carriage movable back and forth over said bed, a roller frame pivotally mounted on said carriage to swing about a horizontal transverse axis, a platen roller mounted on said frame, means for latching said frame in lowered position, manually operable means for releasing said latching means at any stage of movement of the carriage, said roller frame being provided with a handle for operating it and said manually operable releasing means comprising a manually operable member operable by the hand holding said handle, and a rock shaft actuated by said manually operated member extending from a position adjacent the handle to a position adjacent the side of the carriage.
